TUB AND SHOWER FITTING

Loie Condé and Chester W. Hathaway, Decatur,
Ill., assignors to Mueller Co., Decatur, Ill., a
corporation of Illinois

Application March 29, 1934, Serial No. 718,049

13 Claims. (Cl. 4-148)

The present invention relates to fluid controlling and regulating devices and as here shown is disclosed in connection with a combination bath tub and shower fixture.

5 In the drawings herewith, are shown several adaptations of the invention, but it will be understood that these are merely illustrative and in no sense restrictive, as the invention may be developed in various mechanical ways.

10 In the drawings:

Figure 1 is a view in elevation of so much of a tub and shower fixture as is necessary to illustrate my invention, portions of the fixture being in section to show the interior make-up and assembly.

15 Figure 2 is a view on an enlarged scale of the valve chamber and valve.

Figure 3 is a sectional view on substantially the line 3—3 of Fig. 1.

20 Figure 4 is a view in side elevation of a tub and shower fixture with a mixing valve, having my invention applied thereto.

25 Figure 5 is a view in side elevation, the parts being in section of so much of a fixture as is necessary to show the regulating or back pressure valve between the shower and tub spout disposed at a different point in the waterway, and

30 Figure 6 is a view similar to Figure 4 showing the regulating or back pressure valve between the shower and the tub spout disposed at another point in the waterway.

35 Referring to the drawings by numbers, like numbers referring to like parts in the several views, 10 indicates any usual tub fixture having cold and hot water supplies and provided with a tub spout 11. Extending upwardly from the fixture 10 and here shown as formed integral and in vertical alignment with the spout outlet is a shower pipe 12 having a valve chamber. 40 From this valve chamber extends a pipe leading to the shower.

45 The spout 11 will be provided at any suitable point with a valve 13 adapted to be manipulated to open and close the spout and act, when closed, as a diverter to divert water to the valve chamber and shower pipe. As this diverter valve 13 may be of any usual or suitable type, either manually operated or automatic, which will serve to open and close the spout passage, it is unnecessary to 50 illustrate or describe it in detail.

55 The shower pipe 12 is provided at any suitable point in its length, with a valve casing 14 having a valve seat 15 against which is seated a back pressure valve 16 provided with a stem 17 passing through a member 18 which serves to guide

the stem, said member 18 being preferably screw-threaded into the inwardly projecting lugs 19 integral with the wall of the valve casing, which lugs are spaced as shown in Figure 2 to provide water passages 20. Between the member 18 and the valve 16 is a spring 21 tending to hold the valve always to its seat and this spring 21 may be graduated as to strength to meet the different water pressures encountered in different localities and graduate the opening of the valve 16 10 in accordance with these varying pressures. This is readily accomplished by determining the pressure in the particular locality where the installation is to be made and providing a spring of the requisite strength to take care of such pressures. 15

Depending from the valve 16 is a sleeve 22 which has a sliding fit with the port or passage through the web 23. The sleeve 22 is provided with one or more water passages 24, two being here shown which, when the valve is seated as shown in Figure 1, are closed, but when the valve is moved to its upper position, as shown in Figure 3, are opened to provide waterways into the valve chamber. Depending from the valve 16 is a sleeve 22 having a sliding fit with the port or 20 passage through the web 23. This perforated sleeve 22 has two functions. It keeps the water substantially shut off until the valve has reached its full open position, whereupon water will flow through the openings 24 past the valve 16. It 25 has the further function of substantially shutting off the water on downward movement of the valve 16 before the latter reaches its seat, thus acting as a preliminary valve to prevent wire drawing of the valve and hammering. It will be 30 seen that the openings 24 are disposed symmetrically relative to each other, the two openings here shown being on opposite sides of the sleeve in balanced relation so that there will be no tendency in opening or closing of the valve to lateral 35 movement of the valve. Furthermore, the openings are of a shape, here shown as round, to give a gradually decreasing area toward their ends, thus providing for a gradual opening and closing 40 of flow through such openings and past the valve. 45

In the fixture described the water coming from the supply faucets will normally flow through the spout 11, it being understood that the diverter valve 13 in the tub spout will be normally open 50 and the spring valve 16 will be closed, as shown in Figure 1, shutting off communication to the shower, the valve closing spring 21 being so regulated relative to the water pressure that when the spout 11 is open, back-pressure coming from the 55

supply will be insufficient to raise the check valve 16.

When it is desired to use the shower the diverter valve 13 will be closed and the pressure of the water at once diverted to the valve 16 leading to the shower. The closing of the tub spout and diversion of the water to the shower will, of course, build up sufficient pressure to raise the valve 16 from the closed position shown in Figure 1 to the open position shown in Figure 2 and permit the water to pass to the shower. When the supply is turned off or the diverter valve 13 is again opened, the spring check valve 16 will immediately close and cut off all communication with the shower pipe.

The form of the invention shown in Figure 4 is identical, so far as the valve controlling the shower passage is concerned, with that shown in the disclosure in Figures 1, 2, and 3, but it is adapted to tub and shower fixtures of the mixing valve type.

In Figure 4, 25 indicates a mixing valve of any suitable or desired type, which mixing valve receives hot and cold water supplies from the inlet pipes 26, conventionally shown, in the usual manner. The pipe 27 delivers from the mixing valve to the tub spout 28, which is provided with any desired type of diverter valve 29, either manual or automatic, which will serve to close the tub spout and divert the water to the shower.

From the mixing valve the shower pipe 30 extends upwardly and at any suitable point in the shower pipe 30, preferably, as here shown, adjacent the mixing valve casing is the valve casing 31 containing the valve 32 identical in all respects with that valve heretofore described in connection with the adaptation shown in Figures 1 and 2.

The same operation takes place as described in connection with the other adaptations. When the diverter valve 29 is open the flow will be to the tub and the valve 32 will be held to its seat and prevent passage of water to the shower. On closing of the diverter valve 29, the water will be diverted against the valve 32 which will be opened and permit the water to pass to valve chamber 31 and the shower pipe. On cutting off the water supply or opening of the diverter valve 29, the valve 31 will immediately return to its seat and close the passage to the shower.

It will be seen that by means of a back pressure valve in the waterway normal flow will be always through the tub spout and the shower pipe and shower will not be subjected to pressure tending to cause dripping at the shower head, for with the back pressure valve closed and the diverter valve in the tub spout open, there can be no pressure in the shower pipe and shower head.

In the adaptation of the invention shown in Figure 5, the invention is adapted to a concealed fixture located behind the wall indicated by the line 33, tub spout 34, and waterway 35 being provided to which waterway the supply inlet 36 delivers, and if hot and cold water be used or a mixing valve provided, there will, of course, be two inlets 36 opposed to each other, for the hot and cold water and delivering to the waterway 35.

Let into the waterway at a point between the tub spout and the shower connection 37 is the regulating or back pressure valve 38 identical in construction and operation with the valve heretofore described.

In order that access may be had to the valve 38 for repair, replacement, or adjustment, where the fixtures are concealed behind the wall, as shown in Figure 5, there is provided an exten-

sion 39 projecting, as here shown, at substantially right angles, to the supply pipes 35 and 37 for the tub spout and shower, this extension 39 being provided with a closure cap 40 at its outer end. It will be observed that the valve 38 is disposed at right angles to the main waterway or supply pipe and is aligned and centered with respect to the extension 39 so that it is readily accessible by removing the cap 40 and then by suitable tools the valve 38 may be adjusted or manipulated or bodily removed through the extension 39, thus doing away with the necessity of having to work in the confined space behind the wall, or providing a work opening in the face of the wall 33, as otherwise would be the case.

In the adaptation of the invention shown in Figure 6, the regulating or back pressure valve between the shower and the tub spout is disposed at another point in the waterway or supply pipe and so constructed that it is removable as a unit from the line to permit ready substitution of other units, or for purposes of regulating, repairing, or replacing the back pressure valve.

In this adaptation of the invention the parts are concealed behind the wall 41, tub spout 42 projecting therefrom and receiving its supply from the waterway or supply pipe 43 which has the inlet 44, and if hot and cold water is to be used, two inlets to control these supplies, the water supply being controlled by suitable faucets, 30 not shown, which will project through the wall in the usual manner, or if a mixing valve be used, by means of the mixing valve, the handle of which will project through the wall in convenient position for manipulation, as shown in the form of 35 the invention disclosed in Figure 4.

The regulating and back pressure valve 45 is identical in its internal make-up and operation with the valve heretofore shown and described, and is mounted in a fitting 46 provided with a 40 valve seat, seating spring, and a member to serve as a valve guide, exactly as in the construction heretofore described. The fitting 46 is provided at its ends with coupling means designed to be coupled into the shower arm, as shown, and that 45 coupling means may be any usual desired type, there being here shown a screw threaded coupling 47. The fitting may be provided with any suitable means for setting it up or removing it, as for example, a nut portion 48 may be provided if 50 desired.

With the back pressure valve disposed as shown in Figures 5 and 6, there will be no pressure exerted in the shower pipe or head when the valve is closed, which pressure would tend to cause 55 dripping at the shower head, and the supply pipes behind the back pressure valve can, of course, drain downwardly to the tub spout.

Such departures from the constructions here disclosed as amount only to mechanical skill may 60 be made without departing from the range of the invention.

We claim:

1. In a combined tub and shower fixture, the combination of a fluid delivery member having a 65 tub outlet member and a shower outlet member, an inlet member to supply said tub and shower members, a diverter valve controlling flow from said tub outlet member, and a normally closed valve controlling flow in said shower outlet member 70 which opens under fluid pressure when said diverter valve is closed.

2. In a combined tub and shower fixture, the combination of a fluid delivery member having a tub outlet member and a shower outlet member, 75

- an inlet member to supply said tub and shower members, a manually-operated diverter valve controlling flow from said tub outlet member, and a normally closed automatically operable valve controlling flow in said shower outlet member which opens under fluid pressure when said manually-operated diverter valve is closed. 5
3. In a combined tub and shower fixture, the combination of a fluid delivery member having a tub outlet member and a shower outlet member, an inlet member to supply said tub and shower members, a diverter valve in said tub outlet member controlling flow therefrom, and a normally closed automatically operable valve in 10 said shower outlet member controlling flow thereto which opens under fluid pressure when said diverter valve is closed. 15
4. In a combined tub and shower fixture, the combination of a fluid delivery member having a tub outlet member and a shower outlet member provided with a valve chamber, an inlet member to supply said tub and shower members, a diverter valve in said tub outlet member controlling flow therefrom, and a normally closed spring 20 valve in the valve chamber of said shower outlet member which opens under fluid pressure when said diverter valve is closed. 25
5. In a combined tub and shower fixture, the combination of a fluid delivery member having a tub outlet member and a shower outlet member provided with a valve chamber, a diverter valve in said tub outlet member controlling flow therefrom, a normally closed spring valve in the valve chamber of said shower outlet member 30 which opens under fluid pressure when said diverter valve is closed, and means for guiding the movements of said spring valve in said valve chamber. 35
6. In a combined tub and shower fixture, the combination of a fluid delivery member having a tub outlet member and a shower outlet member provided with a valve chamber, a diverter valve in said tub outlet member controlling flow therefrom, a normally closed spring valve in the valve 40 chamber of said shower outlet member which opens under fluid pressure when said diverter valve is closed, and means above and below said spring valve for guiding its movements in said valve chamber. 45
7. In a combined tub and shower fixture, the combination of a fluid delivery member having a tub outlet member and a shower outlet member provided with a valve chamber, an inlet member to supply said tub and shower members, a diverter valve in said tub outlet member controlling flow therefrom, a normally closed spring 50 valve controlling flow in said shower outlet member which opens under fluid pressure when said diverter valve is closed, and a hollow port-engaging valve-guiding sleeve projecting from said valve member. 55
8. In a combined tub and shower fixture, the combination of a fluid delivery member having a tub outlet member, a shower outlet member provided with a valve chamber, an inlet member to supply said tub and shower members, a diverter valve in said tub outlet member controlling flow therefrom, a normally closed spring valve controlling flow in said shower outlet member which 60 opens under fluid pressure when said diverter valve is closed, and a hollow port-engaging valve-guiding sleeve provided with apertures to effect gradual reduction of flow during closing movement of said valve. 65
9. In a combined tub and shower fixture, the combination of a fluid delivery member having a tub outlet member and a shower outlet member provided with a valve chamber, an inlet member to supply said tub and shower members, a diverter valve in said tub outlet member controlling flow therefrom, a normally closed valve controlling flow in said shower outlet member which opens under fluid pressure when said diverter valve is closed, and a tool receiving chamber having a removable closure to permit accessibility to said valve when said closure is removed. 70
10. In a combined tub and shower fixture adapted to be concealed behind a wall, the combination of a fluid delivery member, a tub outlet member projecting through the wall, a shower outlet member projecting through the wall and provided with a valve chamber, a tool receiving chamber member extending from said valve chamber member through the wall to permit accessibility to a valve in said chamber, an inlet member to supply said tub and shower members, a diverter valve in said tub outlet member controlling flow therefrom, and a normally closed valve controlling flow from said shower outlet member which opens under fluid pressure when said diverter valve is closed. 15
11. In a combined tub and shower fixture adapted to be concealed behind a wall, the combination of a fluid delivery member having a tub outlet member and a shower outlet member provided with a valve chamber member disposed between said tub and shower outlets at an angle thereto, a tool receiving chamber member communicating with said valve chamber and projecting through the wall to permit accessibility to said valve, an inlet member to supply said tub and shower members, a diverter valve in said tub outlet controlling flow therefrom, and a normally closed valve in said outlet which opens 20 under fluid pressure when said diverter valve is closed. 25
12. In a combined tub and shower fixture adapted to be concealed behind a wall, the combination of a fluid delivery member having a tub outlet member and a shower outlet member provided with a valve chamber member disposed between said tub and shower outlets at an angle thereto, a tool receiving chamber member aligned with said valve chamber and projecting through 30 the wall to permit accessibility to said valve, an inlet member to supply said tub and shower members, a diverter valve in said tub outlet controlling flow therefrom, and a normally closed valve in said outlet which opens 35 under fluid pressure when said diverter valve is closed. 40
13. In a combined tub and shower fixture adapted to be concealed behind a wall, the combination of a fluid delivery member having a tub outlet member and a shower outlet member, a valve chamber member disposed between said tub outlet and said shower outlet at right angles thereto, a tool receiving chamber member disposed in line with said valve chamber and projecting through the wall to permit accessibility 45 to said valve, an inlet member to supply said tub and shower members, a diverter valve in said tub outlet controlling flow therefrom, and a normally closed valve in said outlet which opens under 50 fluid pressure when said diverter valve is closed. 55
